ULTRASONIC MOTION-DETECTOR HOUSING

Richard L. McMaster, Rochester, N.Y., assignor to
Detection Systems, Inc., Fairport, N.Y.

Filed Mar. 30, 1973, Ser. No. 346,253

Term of patent 14 years

Int. Cl. D29—02

U.S. Cl. D10—106

FIG. 1

FIG. 2

FIG. 1 is a perspective view showing the front, left side and top of my new design for an ultrasonic motion-detector housing; and

FIG. 2 is a perspective view showing the rear, left side and bottom of the housing.

The right side of the housing is identical to the left.

I claim:

The ornamental design for an ultrasonic motion-detector housing, as shown and described.
